UNITED STATES PATENT OFFICE.

HYMEN L. LIPMAN, OF PHILADELPHIA, PENNSYLVANIA.

DESIGN FOR A FRAME FOR EYELET-MACHINES.

SPECIFICATION forming part of Design No. 16,844, dated August 10, 1886.

Application filed May 15, 1886. Serial No. 202,334. Term of patent 7 years.

To all whom it may concern:

Be it known that I, HYMEN L. LIPMAN, a citizen of the United States, residing in the city and county of Philadelphia, State of Pennsylvania, have invented and produced a new and original Design for Eyelet-Machines, of which the following is a specification, reference being had to the accompanying drawing, forming part thereof.

10 The leading feature of my design for the frame of an eyelet-machine is a boss of curved form, having the upper and lower halves of its end pieces of different diameters.

15 My invention consists in a design for the frame of an eyelet-machine, the parts being of new and peculiar forms and having distinctive ornamental features, as shown in the accompanying drawing, in which—

A represents the base, and of elongated form, 20 with straight-lined sides and ends curved substantially as shown in the drawing, and B the neck portion thereof, the latter being of a

curved or rounded form with ornamentations thereon, as shown.

C represents the boss, having both its upper 25 and lower end parts of circular form, the upper being of less diameter than the lower, (the said end parts having ornamentations thereon,) as shown.

E represents a tubular portion pending from 30 the head, the said tubular portion being of the form of a flattened cylinder, as shown.

I claim—

The design for the frame of an eyelet-machine, having a base part, A, the curved neck 35 B, the boss part C, and the tube part E, said boss part E having the upper half of the end pieces of less diameter than the lower ends thereof, all substantially as shown.

HYMEN L. LIPMAN.
